UNITED STATES PATENT OFFICE

112,294

DESIGN FOR A PLASTIC SHEET OR SIMILAR ARTICLE

Harry E. Smith, Short Hills, N. J., assignor to
Celluloid Corporation, a corporation of New
Jersey

Application September 29, 1938, Serial No. 80,136

Term of patent 7 years

To all whom it may concern:

Be it known that I, Harry E. Smith, a citizen of the United States, residing at Short Hills, county of Essex, State of New Jersey, have invented a new, original, and ornamental Design for a Plastic Sheet or Similar Article, of which the following is a specification, reference being had to the accompanying drawing, forming part thereof.

In the accompanying drawing:

Figure 1 is a plan view of a plastic sheet or similar article embodying my new design;

Figure 2 is a plan view of a plastic sheet or similar article bent into the form of a tube showing my new design; and

Figure 3 is an end view of the sheet shown in Figure 1.

The dominant feature of the design is the ornamentation appearing in or on the sheet. The thickness and geometric configuration of the sheet is immaterial. The variations in the shaded effects shown in the drawing are the result of light reflections from the many slanting facets, which facets are in different planes and some of which overlap, and these vary in intensity with the angle at which the sheet or article is viewed.

I claim:

The ornamental design for a plastic sheet or similar article, substantially as shown and described.

HARRY E. SMITH.
